INVENTOR

William Wenderhold

UNITED STATES PATENT OFFICE.

WILLIAM WENDERHOLD, OF NEW YORK, N. Y., ASSIGNOR, BY MESNE ASSIGNMENTS,
TO CRU PATENTS CORPORATION, A CORPORATION OF NEW YORK.

LENS SUPPORT.

Application filed January 14, 1918. Serial No. 211,841.

To all whom it may concern:

Be it known that I, WILLIAM WENDERHOLD, a citizen of the United States, residing at New York, in the county and State of New York, have invented certain new and useful Improvements in Lens Supports, of which the following is a clear, full, and exact description.

My invention relates to an improvement in lens supports, especially such as used in projection apparatus.

The object of my invention is to provide a lens holder that can be adjusted to the diameter of the lens and therefore will support lenses of various diameters.

Referring to the drawings,

Fig. 1 is a side elevation, partly in cross-section;

Fig. 2 is a front elevation;

Fig. 3 is an inside view of my invention.

As shown in the drawing, the bar 1 is fastened into my holder in the half casing or plate member 2 by a suitable clamping means. The half casing or plate member 2 is screwed together with the front half casing 3 by means of screws 4 (see Fig. 2). In each half casing are three pivotally mounted jaw arms 5. Three of said arms have threaded studs 6 with nuts 7 thereon to hold a plain lens 8; the other three jaw arms in the other half casing are provided with actual jaws 12 to hold lenses 9 and 10 that are mounted in a housing 11, also called a jacket. The jaw arms 5 can be swung on their pivot 13 so that the extremity which carries the studs 6 or the jaws 12 is moved from or towards the centre point of the holder.

This movement of the jaws is accomplished by means of a cam disk 14, which cam disk

is provided with cam slots 14^a, which engage 40 a pin 5^a, which pins are mounted in the jaw arms 5. The cam disk 14 is mounted between the two sets of jaw arms, and engages the pins of three jaw arms on one side, and the other three on the other side. The cam disk 45 itself is moved by means of a worm 15, which engages a sector portion 14^b of the cam disk 14. The worm 15 is operated by means of the knob 16, which is fastened on the shaft portion 15^a of the worm 15. Thus, by operating 50 the knob 16, the jaw arms can be either opened or closed, and lenses or lens-housings of various diameters can be held quickly and firmly by my device.

While I have shown and described a specific structure embodying the principles of my invention, I wish it to be understood that my invention in its broad scope as defined by the claim is not to be limited or restricted thereto, as many changes in details of construction 60 will readily appear to those skilled in the art without departing from the contemplated spirit and scope of my invention.

What I claim as my invention is:

A lens holder comprising a pair of plate 65 members, a plurality of jaw arms pivotally mounted on each of said members, the jaw arms on one plate member terminating in clamping screws for holding one lens, and the jaw arms on the other plate member terminating in hooks for holding a lens housing, pins carried by said jaw arms, a movable member adapted to engage said pins, and a worm gear for moving said member.

Signed at the city of New York, State of 75 New York, this 9th day of January, 1918.

WILLIAM WENDERHOLD.
